Patented Nov. 2, 1920.

FIG. 1.

FIG. 2.

UNITED STATES PATENT OFFICE.

STANLEY ZYSKOWSKI, OF CHESTER, PENNSYLVANIA.

SHADE-ROLLER AND CURTAIN-POLE SUPPORTING BRACKET.

1,357,605.

Specification of Letters Patent. Patented Nov. 2, 1920.

Application filed March 9, 1920. Serial No. 364,574.

To all whom it may concern:

Be it known that I, STANLEY ZYSKOWSKI, a citizen of Poland, residing at Chester, in the county of Delaware and State of Pennsylvania, have invented certain new and useful Improvements in Shade-Roller and Curtain-Pole Supporting Brackets, of which the following is a specification.

This invention relates to certain new and useful improvements in shade roller and curtain pole supporting brackets particularly adapted for readily permitting the hanging of shades and curtains in front of windows or the like in proper relation with respect to each other and to give the best possible appearance.

The primary object of the present invention is to provide a simple and efficient form of shade roller supporting bracket and an equally simple and durable form of curtain pole supporting bracket, the two brackets being adjustably associated in a simple and efficient manner for permitting the ready vertical or outward adjustment or both of the pole supporting bracket relative to the shade supporting bracket.

Another object of the invention is to adapt, by slight modification, the usual form of shade roller supporting bracket for receiving and effectively supporting a curtain pole supporting member.

With the above general objects in view and others that will appear as the nature of the invention is better understood, the same consists in the novel form, combination and arrangement of parts hereinafter more fully described in connection with the accompanying drawing.

In the drawing wherein like reference characters designate corresponding parts throughout the several views,

Figure 1 is a view partly in side elevation and partly in vertical section of a bracket constructed in accordance with the present invention, the curtain pole supporting member of the bracket being shown by dotted lines in an outwardly and upwardly adjusted position.

Fig. 2 is a front elevational view of the device shown in Fig. 1,

Fig. 3 is a top plan view thereof,

Fig. 4 illustrates in side elevation a modification of the invention, the curtain pole supporting member being broken away, and

Fig. 5 is substantially a front elevational view of the device shown in Fig. 4.

Referring more in detail to the several views, the present invention embodies a metallic shade roller supporting bracket substantially of the usual form and embodying a plate 5 flanged at its base as at 6 and provided with apertures in said base flange as at 7 for reception of nails or screws in the usual manner for rigidly fastening the bracket to the frame of a window or the like, the plate 5 being provided adjacent its outer end with an aperture 8 in the usual manner for receiving the pintle of a window shade roller. It is of course to be understood that these brackets are employed in pairs, one bracket having the aperture 8 and the other being slotted as at 8' in Fig. 4 in the usual way.

Thus far described, the parts are well known and in common use. However, the top and bottom edges of the plate 5 are, in accordance with the present invention formed with right angular substantially horizontally disposed flanges 9 and 10 which extend laterally of the plate 5 and which respectively have aligned apertures 11 and 12, the flange 9 being notched in a stepped manner as at 13 (see Figs. 2 and 3) at the forward edge of the opening 11 for a purpose which will presently become apparent. The aperture 12 is preferably rectangular.

The curtain pole supporting member of the present device embodies a substantially vertically disposed flat plate 14 which is of any suitable design and which has a straight shank 15 at its lower end serrated as at 16 at its opposite edges so as to form substantially ratchet like teeth for engagement with the flanges 9 and 10 as shown in Fig. 1 when the shank 15 is disposed to extend through the openings 11 and 12. The plate 14 is preferably forwardly enlarged as at 17 above the ratchet teeth 16 so as to provide an abutment capable of resting upon the top flange 9 when said plate 14 is in its lowermost adjusted position. The plate 14 is preferably twisted and shaped at its upper end to provide a curtain pole receiving arm or cradle 18 in the usual way. From the foregoing description it will be seen that when the plate 14 is disposed as shown by full lines in Fig. 1, a tooth of the shank 15 engages a portion of the flange 10 at the rear of the aperture 12 thereof while another tooth engages the flange 9 at one of the notches 13 so that the pole supporting plate 14 is firmly held operatively disposed

through the help of gravity. If it should become desirable to adjust the plate 14 higher or farther away from the window frame for any of many reasons, it will be seen that said plate 14 may be tilted to disengage its teeth 16 from the flanges 9 and 10, whereupon said plate 14 may be slid vertically to the desired height and then tilted back to engage the teeth 16 with the flanges 9 and 10 again. If the plate 14 is positioned as shown in Fig. 3, the same may be slid laterally toward the plate 5 and then tilted forwardly to engage a tooth 16 with the desired one of the notches 13 for permitting positioning of the bracket farther away from the window frame as indicated by dotted lines in Fig. 1.

In Figs. 4 and 5, wherein a modification of the invention is shown, the general structure and principle of the device remains the same although the relative adjustment of the curtain pole supporting member and the shade roller supporting bracket is eliminated. In these figures the shade roller supporting bracket is composed of the usual plate 5' provided with a base flange 6' having fastening device receiving apertures 7' and having laterally extending right angular flanges 9' and 10' upon its upper and lower edges, the flanges 9' and 10' being provided with alined similar slots or openings 11' and 12' which are of narrow elongated form so as to snugly receive the smooth edged shank 15' of the curtain pole supporting member or plate 14'. This plate 14' is provided also with a forward enlargement 17' adapted to rest upon the top flange 9' of the plate 5' whenever the shank 15' is inserted through the apertures 11' and 12' for operatively associating the curtain pole supporting member with the shade roller supporting bracket.

From the foregoing description it is believed that the construction and operation as well as the practicability of the present invention will be readily understood and appreciated by those skilled in the art.

Minor changes may be made without departing from the spirit and scope of the invention as claimed.

What I claim as new is:—

1. A curtain pole and shade roller supporting bracket comprising in combination with the usual shade roller supporting bracket having laterally extending flanges upon the upper and lower edges thereof provided with vertically alined openings, and a substantially vertical curtain pole support-

ing member comprising a plate having a curtain pole receiving arm upon the upper end portion thereof and a substantially straight shank at its lower end adapted for slidable reception in said flange openings. 60

2. A curtain pole and shade roller supporting bracket comprising in combination with the usual shade roller supporting bracket having laterally extending flanges upon the upper and lower edges thereof provided with alined openings, and a substantially vertical curtain pole supporting member comprising a plate having a curtain pole receiving arm upon the upper end portion thereof and a substantially straight shank at its lower end adapted for slidable reception in said flange openings, the shank 70 and the shade roller supporting bracket flanges being co-operatively constructed for permitting vertical adjustment of said curtain pole supporting member relative to said shade roller supporting bracket. 75

3. A curtain pole and shade roller supporting bracket comprising in combination with the usual shade roller supporting bracket having laterally extending flanges upon the upper and lower edges thereof provided with alined openings, and a substantially vertical curtain pole supporting member comprising a plate having a curtain pole receiving arm upon the upper end portion thereof and a substantially straight shank at its lower end adapted for slidable reception in said flange openings, the shank and the shade roller supporting bracket flanges being co-operatively constructed for permitting vertical and outward adjustment of said curtain pole supporting member relative to said shade roller supporting bracket. 90 95

4. A curtain pole and shade roller supporting bracket comprising in combination with the usual shade roller supporting bracket having laterally extending flanges upon the upper and lower edges thereof provided with alined openings, and a substantially vertical curtain pole supporting member comprising a plate having a curtain pole receiving arm upon the upper end portion thereof and a substantially straight shank at its lower end adapted for slidable reception in said flange openings, said curtain pole supporting member being enlarged 100 above said shank to provide an abutment adapted to rest upon the top flange of the shade roller supporting bracket when the device is operatively disposed. 110

In testimony whereof I affix my signature. 115
STANLEY ZYSKOWSKI.
